UNITED STATES PATENT OFFICE.

FREDERICK W. HANKINS, OF PHILADELPHIA, AND CHARLES D. YOUNG, OF WAYNE,
PENNSYLVANIA.

TRUCK PEDESTAL.

Application filed July 7, 1928. Serial No. 291,942.

This invention relates to railway car trucks and more particularly to the construction of the pedestals secured to the wheel pieces or side frames of such trucks. 5 It is a general object of the present invention to provide a novel and improved pedestal construction and assembly for use on railway trucks.

More particularly, it is an object of the 10 invention to provide in a railway truck pedestal a pedestal leg slotted for its full length to allow the insertion of an equalizer together with a novel pedestal strap provided with a spacer or reinforcing member 15 for the slotted leg.

One of the features of the invention comprises the arrangement of a pedestal liner to be engaged between the bottom of a slotted 20 pedestal leg and the pedestal strap and having means thereon to engage with the end of the strap to retain the liner in position.

Other and further features and objects of the invention will be more apparent to those skilled in the art upon a consideration 25 of the accompanying drawings and following specification, wherein is disclosed a single exemplary embodiment of the invention with the understanding, however, that such changes may be made therein as fall 30 within the scope of the appended claims without departing from the spirit of the invention.

In said drawings:

Figure 1 is a side elevation of the end 35 portion of a side frame or wheel piece of a railway truck showing a pedestal and the end of an equalizer bar adapted to rest on top of the journal box carried in the pedestal jaw;

Figure 2 is a transverse vertical section on the line 2—2 of Fig. 1;

Figure 3 is a partial view similar to Fig. 1, but showing the liner in longitudinal section and with one branch of the pedestal 45 leg removed;

Figure 4 is a horizontal section on line 4—4 of Fig. 3; and

Figure 5 is a perspective view of the lower end of a liner.

In a large number of four-wheel railway trucks it is customary to arrange equalizers with their opposite ends resting on the journal boxes at each side of the truck. The 55 wheel pieces or side frames which support the car body through the body bolster are

supported from the equalizers by springs (not shown). These side frames are provided with pedestals to position and guide the journal boxes while allowing them vertical movement. This type of construction is well known. The six-wheel trucks often have a somewhat similar arrangement, using two equalizers to a side, however. In both cases it is difficult to introduce the equalizers through the slots provided for the same in one leg of each pedestal. The present invention contemplates opening this slot from top to bottom of one of the customary slotted legs for each equalizer. The equalizer can then be applied by inserting one end into the short incomplete slot and lifting the other end through the complete slot just described. This materially simplifies the assembly operation, but tends to also weaken the pedestal, for the branches of the slotted leg are not secured together. The present invention provides on the customary pedestal strap or tie bar a projection to extend between the arms or branches of the slotted pedestal leg and to receive a transverse securing means passing through these branches. This projection acts as a spacer or reinforcing member and the securing means which holds it in position also retains the pedestal strap in place.

Referring to the drawings, there is shown at 10 a side frame or wheel piece of a railway truck. In this particular embodiment the pedestal 11 is cast integral therewith and is of hollow box-like construction as are the members of the side frame or wheel piece. The pedestal has the legs 12 and 13. In the four-wheel truck the leg 12 would be closed, i. e., would not have a slot to allow the insertion of an equalizer between the two sides of the leg. The inner face thereof, or the one which would normally engage the journal box, is solid in the leg 12. The leg 13, however, is slotted as shown at 15 in Figures 2 and 4 so that it is divided into the two side branches 16 and 17 open from the junction 18 of the leg with the frame clear to the bottom so that the equalizer 19 may have its end merely lifted into the position shown in Figure 1 between the branches 16 and 17, which act as guides to prevent lateral movement of the equalizer. Suitable reinforcing ribs 21 are provided on the outside of each branch of the leg and those 22 and 23 on the inside. As shown in Fig. 2,

the equalizer is wider at its end 24 where it rests on the journal box than in the portion which passes between the branches of the slotted leg. The bottom of each branch of the leg 13 has a thickened foot member 25.

5 A pedestal tie bar or strap 26 closes the open end of the pedestal jaw to retain the journal box in position. It is secured to the leg 12 in the conventional manner by the 10 passage of a vertical bolt 27 through the strap and through the base or foot 28 of the jaw while the hooked end 29 of the strap engages the end of this foot to assist the bolt in preventing any spreading of the jaw.

15 The opposite end of the strap, which in its main portion has a rectangular cross section of the width of the bases of the legs, passes beneath the portions 25 and has the reduced upstanding portion 30 which passes 20 between the portions 25. It has at its upper end the relatively heavy and wider sleeve 31 the ends 32 of which engage against the inner surfaces of the branches of the leg 13 as shown in Figs. 2 and 4. A bolt 34 passes 25 through suitable openings in the branches and through the bore of the sleeve 31 and retains the sleeve in position. This sleeve acts as a spacer and reinforcing means to hold the branches of the leg spaced in position and 30 at the same time the bolt 34 acts to prevent relative spreading of the two legs of the jaw. It is assisted in this by the sleeve abutting the ribs 23 as shown in Fig. 4. Beneath the vertical extension the wide portion of the strap 35 terminates in the rounded ends 36 as shown in Figs. 1 and 3.

It is desirable that the movement of the box in the pedestal shall not wear directly on the pedestal legs, so suitable liners, preferably of hardened steel or similar material, 40 are arranged to protect the inner faces of the jaws. On the leg 12 this liner takes the form of a sheet having the section 37 resting against the inner face of the jaw and arranged to take the wear of the box. Wings 45 38 engage the sides of the leg to prevent lateral movement of the liner in respect to the jaw and to take the lateral thrust of the box. A tongue 40 projects at right angles to the 50 part 37 and beneath the base 28 of the leg and between it and the strap as shown. This tongue is perforated to allow for the passage of the bolt 27. The tightening of this bolt clamps the tongue in position and the engagement of the bolt with the sides of the 55 hole in the tongue prevents any longitudinal or lateral movement of the liner.

The liner 41 on the slotted leg is somewhat similar in construction to that on the other 60 leg, but its face 42 must be slotted near the top to allow for movement of the equalizer, it being understood that the liner is applied after the equalizer is in position. The liner 41 has wings as in the one just described, and 65 a somewhat similar tongue 43 which is best

shown in Fig. 5. The end of the tongue is slotted as at 44 to provide the arms 45. The portion 43 together with the arms is received between the bases 25 of the branches of the leg and the strap 26, but since the bolt 34 is 70 horizontal instead of vertical, the clamping action here cannot be relied upon to retain the liner in position. The arms 45 therefore engage opposite edges of the extension 30 on the strap to prevent lateral movement of the 75 liner. The ends of these arms are turned down as at 47 so that they engage around the curved end portions 36 of the strap, thereby preventing any longitudinal movement of the strap in the direction of the opposite pedestal 80 leg.

By making the spacer integral with the pedestal strap, a material reduction in the cost of manufacture and in the operation of assembly is effected and by arranging the 85 liner to cooperate with the strap and spacer, no added means are necessary to retain it in position and the operation of assembly is extremely simple. At the same time, the construction is just as effective as those of much 90 more complicated arrangements and the cost of manufacture is materially reduced.

Having thus described the invention, what is claimed as new and desired to be secured by Letters Patent is:

1. In a car truck, in combination, a side frame having a pedestal, one leg of said pedestal being slotted from top to bottom to permit the insertion of an equalizer, a pedestal strap, means on said strap to fit between the branches of said slotted leg, a liner for said slotted leg and means thereon adapted to be engaged between said strap and the slotted leg to retain the same in position.

2. In a car truck, in combination, a side 105 frame having a pedestal, one leg of said pedestal being divided into two lateral branches by a slot permitting the insertion of an equalizer, a pedestal strap extending beneath said legs, means on said strap to fit between said branches, a liner for said branched leg and means thereon to straddle said means on said strap to retain the liner in position when the strap is mounted on said pedestal legs.

3. In a car truck, in combination, a side 110 frame having a pedestal, one leg of said pedestal being divided into two lateral branches by a slot permitting the insertion of an equalizer, a pedestal strap extending beneath said legs, means projecting up from said strap 115 and secured between said branches, a liner for said branched leg, and arms on said liner to straddle said means and fit between the leg branches and said strap.

4. In a car truck, in combination, a side 125 frame having a pedestal, one leg of said pedestal being divided into two lateral branches by a slot permitting the insertion of an equalizer, a pedestal strap extending beneath said legs, means projecting up from said strap 130

and secured between said branches, a liner for said branched leg, arms on said liner to straddle said means and fit between the leg branches and said strap, and means on said 5 liner arms to engage said strap to prevent movement of said liner toward said other pedestal leg.

5. In a car truck, in combination, a side frame having a pedestal, one leg of said pedestal being divided into two lateral branches by a slot permitting the insertion of an equalizer, a pedestal strap extending beneath said legs, means narrower than said strap projecting up therefrom between said branches 10 and secured there, a liner covering the wearing faces of said branches and having a tongue engaged between said strap and the bottom of said branches, said tongue being slotted to provide arms straddling said 15 projection on said strap.

6. In a car truck, in combination, a side frame having a pedestal, one leg of said pedestal being divided into two lateral branches by a slot permitting the insertion of an equalizer, a pedestal strap extending beneath said legs, means narrower than said strap projecting up therefrom between said branches and secured there, a liner covering the wearing faces of said branches and having a tongue engaged between said strap and the bottom of said branches, said tongue being slotted to provide arms straddling said 20 projection on said strap.

jection on said strap, the ends of said arms being turned down to engage the end of said strap.

35

7. In a car truck, in combination, a side frame having a pedestal, legs on said pedestal, one leg thereof being divided into two lateral branches by a slot permitting the insertion of an equalizer, bases on said pedestal 40 legs, a pedestal strap adapted to fit beneath said bases, a projection on said strap extending between said branches to reinforce the same, a liner for said slotted leg and means thereon clamped between said leg and strap 45 to maintain said liner in position.

8. In a car truck, in combination, a side frame having a pedestal, one leg of said pedestal being divided into two lateral branches by a slot permitting the insertion of an equalizer, a pedestal strap extending beneath said 50 legs, means narrower than said strap projecting up therefrom between said branches and secured there, a liner covering the wearing faces of said branches and having a tongue engaged between said strap and the bottom of said branches, a liner for said other leg and having a tongue engaged between said strap and the bottom of that leg, and means to secure the strap to each leg. 55

In testimony whereof we hereunto affix our signatures.
